UNITED STATES PATENT OFFICE.

ARTHUR O. JENNINGS, OF SOUTHPORT, CONNECTICUT.

DESIGN FOR A CLOCK-CASE.

SPECIFICATION forming part of Design No. 15,571, dated November 25, 1884.

Application filed August 14, 1884. Term of patent 7 years.

To all whom it may concern:

Be it known that I, ARTHUR O. JENNINGS, of Southport, county of Fairfield, and State of Connecticut, have invented and produced 5 by my own industry, genius, efforts, and expense a new and original Design for a Clock-Case, of which the following is a correct description, reference being had to the annexed photograph, which represents a face view of 10 my new clock.

In the photograph, the letter A represents the base, B the body, and C the top, of the clock. The base A has a lower ogee molding, a, and above the same an ogee molding, b, which is 15 ribbed vertically, thereby producing a peculiar effect. The body B has on its surface contiguous irregular cell-like depressions d d, as shown. The top C has its lower part, e,

made of flaring form and divided by upright creases into adjoining tapering beads, as 20 shown. Above this lower portion, e, of the top is the molding f; above that the ball g, which carries the ring h.

I claim—

1. The design for a clock-case, the same consisting of the base A, having moldings a b, 25 and body B, having figures d d, substantially as shown.

2. The design for a clock-case, the same consisting of the base A, having moldings a b, 30 body B, having figures d d, and top C, having the parts e f g, substantially as shown.

ARTHUR O. JENNINGS.
